UNITED STATES PATENT OFFICE.

KARL GAMMEL, OF CLEVELAND, OHIO, ASSIGNOR TO THE CLEVELAND MACARONI COMPANY, OF CLEVELAND, OHIO, A CORPORATION OF OHIO.

PROCESS OF DRYING EDIBLE PASTES.

Specification of Letters Patent. Patented Apr. 11, 1916.

1,178,794.

Application filed April 10, 1911, Serial No. 620,179. Renewed September 9, 1915. Serial No. 49,834.

To all whom it may concern:

Be it known that I, KARL GAMMEL, a subject of the Emperor of Germany, residing at Cleveland, in the county of Cuyahoga and State of Ohio, have invented certain new and useful Improvements in Processes of Drying Edible Pastes, of which the following is a specification.

According to the methods of drying generally practised up to the present time, the goods coming fresh from the press are hung over sticks and subjected for a time to a powerful current of air in order that they may be dried sufficiently to permit handling. The goods are then placed in drying chambers where they are allowed to remain for a period of from 5 to 8 days in order to complete the drying. In the drying chambers it is necessary to protect the goods carefully against any injurious influence, such as a current of air, heat radiated from heated bodies, excessive dryness, etc., in order that the goods will not crack or become too strongly bent. If the ventilation is imperfect a mold formation often appears in moist weather, especially if the goods are hung too close together. The varying temperature and humidity of the air cause constant failures. During the preliminary drying above referred to, the goods tend to bend, and the bending becomes permanent unless the drying process is temporarily interrupted either by hanging the goods closely together or by bringing the same into a cool, moist drying chamber. If, however, the bending has proceeded too far, the goods cannot be again straightened by this means, and in most cases the goods become a complete loss on account of bursting and splitting.

According to my improved process the preliminary drying of the goods is unnecessary; there is no interruption of the drying process, and the long period of drying in the drying chambers is entirely avoided. The goods coming fresh from the press are placed over sticks as heretofore and are then subjected immediately to the various steps of my improved process until the goods are completely dried, which is accomplished in a relatively short period of time compared with the period heretofore required.

The accompanying drawing shows one form of apparatus adapted for carrying out my improved process, which comprises a

closed drying chamber *a* having suitable means such as the wing *b* for producing a continuous movement of air therein. Suitable means as the valve controlled pipes *c* having the cocks *c'* therein are provided, whereby fresh air may be admitted and moist air removed from the chamber as desired. The heater *d* of any well known construction is also provided in the chamber to control the temperature thereof. An auxiliary pipe *e* also communicates with the chamber so that vapor can be supplied if necessary or desired in order to regulate and control the humidity of the air.

In practising my improved process the goods are exposed to a continuous movement of air during the entire drying process, which may pass along the goods in any desired direction. The goods are subjected to the air current under normal atmospheric conditions until approximately 60% of the original water contents of the goods has been removed. During this period the air current is directed against the goods with considerable velocity in order to shorten the time of drying as much as possible, since the drying will proceed somewhat in proportion to the velocity of the air current. At this point the goods become quite dry and stiff and begin to bend. In this art the term "to bend" is used in the dictionary sense of "to warp." Thereupon the temperature of the air current is raised so that more moisture will be carried by the air current. The outer portion or layer of the goods will become softened, and the goods will be caused to straighten under their own weight, and without stopping or interrupting the drying process or discontinuing the air current. During this period, and while the goods are being straightened by their own weight, the velocity of the air current may, if desired, be decreased, but may again be increased to its original velocity when the goods are straightened. If the air current is continued, even though the said current has a higher temperature, the outer portion or surface of the goods will again become dried very hard and stiff and the goods will commence to bend. Thereupon the temperature of the air current is again raised to increase the absorption of the moisture, thus moistening the outer surface of the goods and permitting the same to straighten under their own weight.

The foregoing operation of heating the air current by successive stages and subjecting the goods to the current of air at each of said stages until the goods become dried, and 5 tend to bend, is continued until the temperature is raised to about 50 or 60° C. By the time this temperature has been reached, the goods have lost the greater part of their water contents and lose their flexibility and 10 become hard. Thereafter the drying process is completed with very little if any change of the air body, and largely by regulating the humidity thereof. During the final step in the drying process the humidity is 15 slightly below the saturation point of the air body, and is controlled in any suitable manner, either by permitting the heat to remain stationary at 50 to 60° C. and introducing small quantities of fresh air at suitable 20 intervals and permitting a corresponding quantity of saturated air to escape or by keeping the air body constant and gradually heating same to about 80° C. in order to raise the saturation point. By this last step the 25 remaining portion of the water contents of the goods is entirely removed, so that the goods can be shipped.

By means of this process the goods can be brought directly to the drying chamber from 30 the press without intermediate operations and handling of any kind, and may be dried practically without interruption and in the presence of continuous air currents, so that the period of time required for the drying 35 process will be greatly reduced.

Although I have shown one form of apparatus for carrying out my process, it is obvious that various other forms of apparatus

Copies of this patent may be obtained for five cents each, by addressing the "Commissioner of Patents. Washington, D. C."

may be employed for this purpose and that many changes and modifications may be 40 made in the apparatus shown which are within the skill of the mechanic without varying or changing the operation of the process.

I claim as my invention:

1. The process of drying edible paste by subjecting the same to the action of air currents until it begins to bend, raising the temperature to draw the moisture to the surface and to straighten the bends, maintaining the 50 raised temperature until the paste again begins to bend and finally subjecting it to air of constant temperature and below the saturation point.

2. The process of drying edible tubes by 55 subjecting the same to air currents of progressively higher temperatures, each temperature being maintained until the tubes begin to bend when the temperature is raised and finally subjecting the tubes to air of substantially constant temperature and below the saturation point.

3. In the art of drying edible paste, the process which consists in subjecting a body of the paste to the action of a current of air 60 until the paste manifests a tendency to bend, raising the temperature to draw the moisture to the surface of the body and finally subjecting the body to the action of air below the saturation point.

This specification signed and witnessed this 13th day of March, A. D. 1911.

KARL GAMMEL.
